PROCESS AND APPARATUS FOR WASHING ARTIFICIAL SILK

Filed April 26, 1923

2 Sheets-Sheet 1

This technical drawing illustrates a circular device, likely a filter or a similar industrial component. The outer boundary is marked with the number 1. The interior is divided into several concentric sections. The innermost section contains a circular component labeled 2, which is connected to a rectangular frame labeled 11. A vertical pipe labeled 13 extends from the bottom of frame 11. The middle section features a series of circular holes labeled 5, arranged in a ring. The outermost section is covered with a mesh or screen labeled 8, supported by a frame labeled 4. A small tube labeled 7 is attached to the top edge of the screen. The entire assembly is shown in a perspective view, highlighting its three-dimensional structure.

UNITED STATES PATENT OFFICE.

ADRIEN PINEL, OF ROUEN, FRANCE.

PROCESS AND APPARATUS FOR WASHING ARTIFICIAL SILK.

Application filed April 26, 1923. Serial No. 634,867.

To all whom it may concern:

Be it known that I, ADRIEN PINEL, a citizen of the French Republic, residing at Rouen, in the Department of Seine-Inférieure and State of France, have invented or discovered certain new and useful Improvements in Processes and Apparatus for Washing Artificial Silk, of which the following is a specification, reference being 10 had therein to the accompanying drawings.

It is known that bobbins of artificial silk as they leave the squirting and coagulating apparatus have to be washed and dried. This washing is necessary for the reason 15 that the cellulose from which the artificial silk is made is impregnated with certain acids and salts which will change the same, both chemically and physically, when the silk is dried, if not eliminated.

20 These two operations such as hitherto carried out, take considerable time. There is, therefore, a considerable accumulation of materials and of bobbins being treated; and an excessive delay in the manufacture.

25 As to the drying, it is possible to reduce its duration by a preliminary drying of the bobbins by centrifugal action. This advantage however is to a great extent neutralized by the time and the supplementary operations which are necessary for placing in and 30 withdrawing the bobbins from the centrifugal drying machine and by the waste which often results therefrom.

The present invention has for its object a 35 rapid and economic washing of bobbins of artificial silk which leave the squirting and coagulating apparatus and at the same time placing them under such conditions that their subsequent drying shall be also more 40 rapid and consequently, more economic.

To this end, the invention has for its object, a method of rapid and economic washing of bobbins of artificial silk consisting in principle, in the combination of successive 45 alternating washings and centrifugal dryings, each being of a comparatively short duration, it being possible to vary this method in any suitable manner and more particularly with a view to increasing the economic 50 character, by means of a new type of washing and centrifugal drying machines, which is also within the present invention.

The above process may be carried into 55 practice in various ways, among others and by way of example, the bobbins to be washed

may be sprayed during a few minutes, then they may be subjected to a centrifugal drying also for a few minutes and these two operations may be alternately repeated, thus obtaining a perfect washing after about one hour of this treatment, the last centrifugal drying operation expelling the liquid which impregnates the bobbins, putting the latter in favourable conditions for a subsequent rapid and economic drying. 60

The duration of the alternating periods of washing and centrifugal drying may be equal or not for each of the operations, they may be increasing or decreasing, and also the duration between each period of washing 70 and centrifugal drying necessary for carrying them out, may constitute a third phase of the process, the duration of which may then be prolonged and become equal or longer or shorter than the duration of the 75 periods of washing and centrifugal drying, the said third period permitting the impregnation of the bobbins sprayed with a small quantity of water and consequently increasing the economy of the process, by reducing 80 the consumption of the washing water.

For carrying the above said principles of the invention into practice, various means may be used, either manual or mechanical; the washing may be effected by spraying, 85 immersion, or circulation, and the drying by means of any centrifugal drying machines; however, in order to do away with any useless, harmful and costly handling of the bobbins, it will be preferable to carry out 90 the process by means of a new type of washing and centrifugal drying machine, permitting the washing and centrifugal drying of the bobbins without handling them, according to the chosen mode of carrying the invention into effect. A machine of this kind may, for instance, be constructed and operated as hereinafter described and diagrammatically illustrated by way of example in the drawings accompanying the present description and in which:

Fig. 1 is a front elevation.

Fig. 2 is a diametral vertical section.

Referring to the drawings, 1 is a frame in which is journalled a horizontal driving shaft 2 to one end of which is fixed a circular carrier 3 from one or both of the faces of which, and near its periphery, extend one, two or a larger number of circular series of bobbin-holders, each consisting 110

preferably of a pair of spindles 4 on which are placed the bobbins 5. In order to maintain the bobbins 5 upon their bobbin-holders 4, during the working of the machine, one 5 of the holders 4 of each pair is provided at its outer end with a small oscillating or rotary projection 6, which allows or prevents, according to its position, the withdrawal or insertion of the bobbins 5. The said projection 10 may, of course, be replaced by any other means for holding the bobbins 5 on the spindles 4.

A water distribution pipe system 7 is arranged outside of the whole or a part of the 15 periphery of the rotary carrier 3, and comprises cross pipes having perforations 8 which are suitable in number and are properly located to spray the bobbins 5, mounted upon the bobbin-holders 4, with jets of 20 water, either during a continuous, but slow, or an intermittent rotation of the member 3.

To this end, the actuation of the bobbin carrier 3, by the shaft 2, will be such, that it will be possible to obtain, at will, either a 25 very high speed of rotation of said carrier, with a view to drying by centrifugal action, or a slower speed of rotation permitting the spraying; or a very high speed for drying by centrifugal action, and a stoppage for 30 spraying, these combinations being capable of being carried into effect by various driving means. Such operations may be effected by the means of an electric motor 9 having a shaft provided with fast and loose pulleys 35 which may be connected by a belt 10 with fast and loose pulleys on the shaft 12. The motor shaft has a suitable connection, shown in dotted lines in Fig. 2, with a shaft which is provided with a worm 12 meshing 40 with a worm-wheel 13 near the lower end of a vertical shaft 11 which is provided near its upper end with a worm meshing with a worm-wheel 14, on the shaft 2. This connection between the motor shaft 45 and the shaft carrying the worm 12 is preferably effected by a pawl which is automatically lifted when the shaft 2 is driven at a high speed by the belt 10 running from a pulley on the shaft of the motor 9. When 50 it is desired to rotate the bobbin-carrier 3 slowly for a washing operation the shaft 2 will be rotated by means of the worm and worm-wheel gearing just described, the belt 10 being at such time shifted to the loose 55 pulleys referred to; but when it is desired to rotate the bobbin-carrier 3 rapidly, for centrifugal drying, the worm and worm-wheel gearing will be disconnected from the motor shaft and the belt 10 will be shifted 60 to the loose pulleys on the motor shaft and the shaft 2. Either the slow or rapid rotations of the bobbin-carrier 3 may be effected intermittently by an intermittent energizing 65 of the electric motor 9, by turning the current off and on, as will be obvious.

A casing, not illustrated, will, in practice, enclose the bobbin-carrier 3 and its spraying system, with a view to avoiding the splashing of liquid which is collected and removed for treatment, if desired, with a view to the 70 recovery of the substances which have been carried off by the washing operation.

With this machine or with any other machine of the same type, constructed or adapted in such a manner as to allow the 75 present process of being carried into effect, according to the above principle, the bobbins to be washed may be treated rapidly and economically, after the bobbins 5 have been mounted upon their holders or supports 4. 80

The bobbin-carrier 3 is caused to rotate very slowly for a few minutes during which the spraying water is projected through the jets 8, upon the bobbins; afterwards, the, 85 delivery of water being stopped, the carrier is caused to rotate rapidly, in such a manner as to effect the centrifugal drying of the bobbins which have just been washed.

After a few minutes of centrifugal drying, the rapid rotation of the carrier 3 is 90 replaced by the very slow one, for allowing a new spraying during a few minutes and so on, alternately, by varying or not the durations of the washings and centrifugal dryings, the bobbins being finally washed after 95 about one hour of such a treatment.

According to the same principle it is possible, after spraying the bobbins, to stop the carrier for a certain time in order that the bobbins may be completely impregnated 100 with the washing water, the centrifugal drying taking place afterwards, and so on, the saving in liquid being thereby still further effected and also the expense in the motive power, the duration of the treatment being 105 about the same as previously.

In certain cases, the washing may take place with the bobbin-carrier 3 stopped, the spraying being replaced by a temporary immersion in water of the whole or part of the bobbins mounted upon the carrier which may be disposed horizontally or vertically, all 110 these variations in the carrying out of the rapid and economic method of washing, according to the present invention, being 115 within the principle of the invention.

What I claim is:

1. A process for treating artificial silk product consisting in alternately washing and drying the same a successive number of times, the washing being effected by spraying and the drying by centrifugal action. 120

2. An apparatus for washing and drying artificial silk product consisting of a rotary bobbin-carrier, spraying means for subjecting the bobbins on said carrier to jets of water, operating means for rotating said carrier slowly for a washing operation and means for rotating said carrier rapidly for 125 a centrifugal drying operation. 130

3. An apparatus for washing and drying artificial silk product consisting of a rotary bobbin-carrier, spraying means for subjecting the bobbins on said carrier to jets of water, operating means for rotating said carrier slowly for a washing operation and means for rotating said carrier rapidly for a centrifugal drying operation, said slow and rapid operating means being adapted 10 to be actuated alternately.

4. An apparatus for washing and drying artificial silk product consisting of a rotary bobbin-carrier, spraying means for subjecting the bobbins on said carrier to jets of water, operating means for rotating said carrier slowly for a washing operation and means for rotating said carrier rapidly for 15 a centrifugal drying operation, said slow

and rapid operating means being adapted to be actuated intermittently. 20

5. An apparatus for washing and drying artificial silk product comprising a bobbin-carrier, a shaft on which said carrier is mounted, an electric motor having a shaft, fast and loose pulleys on both of said shafts, 25 a belt connecting said pulleys, whereby said carrier may be rotated rapidly for centrifugal drying, worm and worm-wheel gearing adapted to be operatively connected with and disconnected from said shafts, for slow 30 rotation of said carrier for a washing operation, and spraying means adjacent said bobbin-carrier.

In testimony whereof I affix my signature.

ADRIEN PINEL.
